UNITED STATES PATENT OFFICE.

CHARLES K. GILES, OF CHICAGO, ILLINOIS.

WATCH-CASE.

SPECIFICATION forming part of Letters Patent No. 367,288, dated July 26, 1887.

Application filed July 18, 1885. Serial No. 172,016. (Model.)

To all whom it may concern:

Be it known that I, CHARLES K. GILES, a citizen of the United States, residing at Chicago, in the county of Cook and State of Illinois, have invented certain new and useful Improvements in Watch-Cases, which are fully set forth in the following specification, reference being had to the accompanying drawings, in which—

10 Figure 1 is a plan view of a watch-case embodying my invention, a portion of the same being broken away to show the construction; Fig. 2, a sectional view of the same taken on the line xx of Fig. 1; Fig. 3, a view of the 15 case-lining and outswinging ring detached; Fig. 4, a view of the case-lining detached without the outswinging ring; and Fig. 5, a transverse sectional view of the case-lining.

Like letters refer to like parts in all the figures of the drawings.

My invention relates to watch-cases, its object being to provide a case-lining which shall prevent access of dust to the movement, while at the same time the movement will be readily accessible for inspection or repair; and to these ends my invention consists in certain novel features, which I will now proceed to describe, and then specifically point out in the claims.

30 In the drawings, A represents the case proper, which is shown as constructed in the same manner as the watch-case shown and described in an application filed by me April 27, 1885, Serial No. 163,658. It will be understood, of course, that I do not limit myself to any particular form of case in the application of my improvement. Within the case proper, A, is fitted a case-lining, B, which is 35 constructed of a shell of metal in a single piece. This case-lining fits snugly within the case proper and is retained in position by any suitable means. In the construction shown, the watch-case being adapted to receive a stem-winding movement, the lining is retained in position by means of the winding-stem, which passes through it, the lining being provided with an aperture, b, to receive the stem. This case-lining B is provided with an 40 outswinging ring, C, which is constructed to

receive the watch-movement. The hinge connection between the movement-holding ring C and case-lining B consists of a separate hinge-piece, D, fitting in a recess, d, in the outer surface of the case-center B and flush 55 with the said surface. This hinge-piece has hinged to it the movement-holding ring C, and is retained in position in the recess or seat d by means of the case proper, A, when the case-lining is in place. This piece D is also in this 60 instance perforated at d' to permit the winding-stem to pass through it.

It will be seen that with the above construction the case-lining, being open only at its upper face, will effectually prevent any 65 access of the dust to the movement from below, since it incloses the movement completely as far as its exposed portions are concerned. At the same time access can be readily had to the movement by turning out 70 the outswinging movement-holding ring which carries the same.

It is obvious that various modifications in the details of construction may be made without departing from the principle of my invention. For instance, the case-lining and outswinging ring may be applied to any suitable form of case, whether hunter or open face. 75

I do not wish to be understood as here claiming anything described and shown in the application of R. E. Fenner, Serial No. 168,286, and I hereby disclaim as of my invention everything that is shown and described in the said Fenner application.

Having thus described my invention, what 85 I claim as new, and desire to secure by Letters Patent, is—

1. The outer case, in combination with a case-lining provided with a recess or seat of irregular shape located between the two said 90 parts and having an aperture to receive the winding-stem, an independent leaf of shape corresponding to said seat and adapted to fit within the latter and perforated for the winding-stem, and a movement-holding ring hinged 95 to said leaf, whereby the said leaf may be locked in position between the case and the lining, substantially as and for the purposes specified.

2. The outer case, A, in combination with 100

the case-lining B, provided with a recess or seat, *d*, in its outer surface, the back portion of which is wider than the front, and having an aperture, *b*, for the winding-stem, and the independent leaf D, shaped like the recess *d*, which it is adapted to closely fit, and perforated at *d'* for the winding-stem, and the

movement-holding ring C, hinged to the leaf D, substantially as and for the purposes specified.

CHARLES K. GILES.
